UNITED STATES PATENT OFFICE.

KARL MAIER, OF STUTTGART, GERMANY, ASSIGNOR TO UNION SPECIAL MASCHINENFABRIK GESELLSCHAFT MIT BESCHRÄNKTER HAFTUNG, OF STUTTGART, GERMANY.

WHIP-STITCH SEWING-MACHINE.

No. 832,740.

Specification of Letters Patent.

Patented Oct. 9, 1906.

Application filed January 18, 1905. Serial No. 241,697.

To all whom it may concern:

Be it known that I, KARL MAIER, a citizen of the German Empire, residing at Stuttgart, in the Kingdom of Würtemberg, Germany, have invented certain new and useful Improvements in Whip-Stitch Sewing-Machines, of which the following is a description, reference being had to the accompanying drawings and to the figures of reference marked thereon.

My invention relates to overseaming-machines of the type wherein the needle-loop is passed through the material adjacent the edge thereof and a looper-thread is passed through said needle-loop, which is in turn either directly or indirectly engaged with the needle-loop upon the upper surface of the work by a spreader.

My invention consists in novel mechanism for supporting and operating the looper, whereby the same is caused to enter and leave the needle-loop rapidly, while the same when out of the loop moves more slowly. By this rapid movement of the looper entering and leaving the needle-loop a relatively small loop of needle-thread is formed on the under side of the material, thus avoiding the reeving of the needle-thread through the fabric, and a much cheaper quality of thread may be used—such as twisted cotton, jute, yarn, and the like—and a broad hem covering over the edge of the material may be made.

My invention consists, further, in details of construction and combinations of parts which will be hereinafter described, and pointed out in the claims.

In the drawings, Figure 1 is a side elevation of a machine embodying my invention, certain parts being omitted for the sake of clearness. Fig. 2 is a top plan view of an overseam made on my machine. Fig. 3 is a bottom plan view of the overseam shown in Fig. 2. Fig. 4 is a top plan view of an overseam made on my machine when the spreader is a thread-carrying member, the overseam in this instance being composed of three threads. Fig. 5 is a bottom plan view of the overseam shown in Fig. 4. Fig. 6 is a side view of the spreader, together with the immediate mechanism for supporting and operating the same. Some of the parts appear in perspective, as the axis of the spreader is inclined to the horizontal. Fig. 7 is an end view of the parts shown in Fig. 6. Fig. 8 is a

side elevation of the looper and the immediate mechanism for supporting and operating the same. Fig. 9 is a top plan view of the parts shown in Fig. 8. Fig. 10 shows in perspective the relative arrangement of the needle, looper, and spreader, together with the fabric, when the needle has thrown out its loop and the looper is about to enter the same. Fig. 11 is a view similar to that shown in Fig. 10, the looper having entered the needle-loop and the spreader having engaged the looper-thread loop preparatory to carrying the same over the edge of the fabric. Fig. 12 is a fragmentary perspective view of the needle and spreader, wherein the spreader is presenting the looper-loop to the needle. Fig. 13 is a modification wherein the spreader is a thread-carrying implement, which in its movements enters the looper-loop and presents its thread to the needle; and Fig. 14 is a section through the fabric, showing the position of the needle-thread loops in the finished overseam relative to the fabric.

The machine-frame 1 is of the usual form, carrying bearings at its forward end, in which reciprocates the needle-bar carrying a needle 2. The needle-bar is reciprocated by the usual gooseneck-lever 22, pivoted on the machine-frame and operatively connected to an eccentric carried by the main shaft and operated by the usual belt-wheel 3. The needle in its operation passes through the fabric adjacent the edge thereof and, rising, throws out a loop for the looper to enter, as clearly shown in Fig. 10.

The thread-carrying looper 4 moves beneath the needle-plate 5 and closely behind the needle 2. Said looper 4 is carried by a looper-stem 41, mounted on shaft 42, supported in a bearing 43 on the machine-bed. At the opposite end of the shaft 42 is an arm 14, rigidly connected to said shaft, so that any movement of said arm is communicated to the looper. Extending upwardly from the bed of the machine are two separated brackets carrying at their upper ends bearings for a shaft 60. Mounted on said shaft 60 is a sleeve 61, carrying two arms 62 62, carrying in turn another shaft or bearing 63. Loosely mounted on the shaft 63 are two arms 13 13, arranged, respectively, adjacent the arms 62 62. Between the arms 13 13 and loosely connected to the shaft 63 is a link 12. The opposite ends of the arms 13 13 embrace

the end of the arm 14 and are pivotally connected thereto. It will be noted that the arms 62 62 and the arms 13 13 constitute a system of toggle-levers. It will also be noted that the path of movement of the free end of the arm 14 is substantially in a vertical line containing the shaft 60. The toggle-levers moving from a position on one side of the vertical line or longitudinal axis of the toggles to a corresponding position on the other side will move the looper 4 forward and back, making a complete reciprocation of said looper, and the toggles in moving back to position shown in Fig. 8 will again reciprocate the looper. Thus it will be seen that the looper has two complete reciprocations to one reciprocation of the toggle-lever. The link 12 is in turn pivoted to a bell-crank lever 11, fulcrumed on the machine-frame, and at its other end connected by a link 10 to an eccentric 8. Said eccentric is carried by a gear-wheel 9, freely supported on a stud 90, secured to the main frame of the machine. The proportions of the gear-wheels are such that the gear-wheel 9 revolves once while the gear-wheel 91 revolves twice. In other words, the gear-wheel 9 has a one-to-two movement. It will be noted that the timing of the vertical movement of the link 10 will be the same as the vertical component of movement of the eccentric 8—that is, there is first a relative slow movement from the extreme upper position, increasing to a maximum at ninety degrees, then decreasing to zero at its lowest point at one hundred and eighty degrees, increasing again to two hundred and seventy degrees, &c.

From the above statements it will be seen that the looper is reciprocated twice to each revolution of the eccentric 8, also that the looper is in its withdrawn position (see Fig. 1) when the eccentric is at its highest point, and as the eccentric moves to its lowest position the looper is moved forward into the needle-loop and withdrawn. While the looper is in the needle-loop the vertical movement of the link 10 is relatively very rapid, and consequently the looper moves forward slowly, increased in speed as it enters the loop, and while in the loop the same moves very rapidly. This rapid movement of the looper while in the needle-loop allows a much smaller loop of needle-thread to be thrown out, and thus avoids much of the reeving of the thread through the material, and a poor quality of thread can be used.

The spreader 16 (shown in detail in Figs. 6 and 7) has a forked thread-engaging end. This spreader 16 is pivotally mounted intermediate its ends on a link 17, which in turn is pivoted on a stud 170, carried by a standard 19. Said standard is formed integral with the base 19^a and projects upwardly toward the operator. The stud 170, which is at right angles to the standard 19, is thus inclined to

the bed-plate, and consequently the spreader swinging on the link 17 moves in a plane cutting the horizontal plane containing the work-support at an acute angle. The spreader is given its movements about the link 17 by a rock-shaft 20, which is pivoted between the standards 19 and 190. The arm 18 of the rock-shaft is forked and pivotally connected to the spreader, while the other arm of the rock-shaft is connected by the link 21 to the arm 22 of the needle-vibrating arm. The support for the spreader is so disposed relative to the needle 2 that the spreader moves from a position behind the needle beneath the bed-plate, up over the edge of the material, to a position in front of the needle, the spreader in its movement engaging the looper-loop 15 and carrying the same into position to be engaged by the needle. The resulting seam is that shown in Figs. 2 and 3. If, however, the spreader be a thread-carrying implement, as shown in Fig. 13, said spreader, with its thread 23, would pass through the looper-loop 15 and deposit a loop of the spreader-thread in a position to be entered by the needle, and the resulting seam would be that shown in Figs. 4 and 5.

Various minor modifications and changes in the construction and arrangement of the parts may be made without departing from the spirit of my invention, and it will be understood that as far as the broad features are concerned I do not wish to be limited to the details of construction.

Having thus described my invention, what I claim as new, and desire to secure by Letters Patent, is—

1. In an overseaming-machine, the combination with a needle and means for operating the same, of complementary stitch-forming mechanism, comprising a looper and means for operating the said looper including toggle-levers, said toggle-levers moving across the longitudinal axis of said toggles, whereby the looper is given two complete reciprocations to one reciprocation of the toggles; substantially as described.

2. In an overseaming-machine, the combination with a needle and means for operating the same, of complementary stitch-forming mechanism, comprising a spreader, means for operating the said spreader, a looper, and means for operating the said looper, including toggle-levers, said toggle-levers moving across the longitudinal axis of said toggles, whereby the looper is given two complete reciprocations to one reciprocation of the toggles; substantially as described.

3. In an overseaming-machine, the combination with a needle, and means for operating the same, of complementary stitch-forming mechanism, comprising a spreader, a support for said spreader, said support being inclined to the bed-plate whereby the spreader moves from a position behind the needle below said

- bed-plate to a position in front of said needle above the same, means for operating said spreader, a looper, and means for operating the said looper including toggle-levers, said 5 toggle-levers moving across the longitudinal axis of said toggles, whereby the looper is given two complete reciprocations to one reciprocation of the toggles; substantially as described.
- 10 4. In a sewing-machine, the combination of the main shaft, a needle, means for operating the same and complemental stitch-forming mechanism comprising a looper, and means for operating said looper including a 15 rotating member, means for rotating said member once to two rotations of the main shaft, a member reciprocated by said rotating member, and means connecting said looper and reciprocating member, said connecting means reciprocating said looper twice to each reciprocation of the reciprocating member; substantially as described.
- 20 5. In an overseaming-machine, the combination of the main shaft, a needle, means for operating the same and complemental stitch-forming mechanism, comprising a spreader, means for operating said spreader, a looper, and means for operating said looper including a rotating member, means for rotating said 25 member once to two rotations of the main shaft, a member reciprocated by said rotating member, and means connecting said looper and reciprocating member, said connecting means reciprocating said looper twice to each reciprocation of the reciprocating member; substantially as described.
- 30 6. In an overseaming-machine, the combination of the main shaft, a needle, means for operating the same and complemental stitch-forming mechanism comprising a looper, and means for operating said looper including a rotating member, means for rotating said member once to two rotations of the main shaft, an eccentric portion carried by said rotating member, and means connecting said eccentric portion and said looper, whereby said looper is reciprocated twice to each rotation of said eccentric portion; substantially as described.
- 35 7. In an overseaming-machine, the combination of the main shaft, a needle, means for operating the same and complemental stitch-forming mechanism comprising a spreader, means for operating said spreader, a looper, and means for operating said looper including a rotating member, means for rotating said member once to two rotations of the main shaft, an eccentric portion carried by said rotating member, and means connecting said 40 eccentric portion and said looper, whereby said looper is reciprocated twice to each rotation of said eccentric portion; substantially as described.
- 45 8. In an overseaming-machine, the combination of the main shaft, a needle, means for operating the same and complemental stitch-forming mechanism comprising a spreader, a looper, toggle-levers, said toggle-levers moving across the longitudinal axes of said toggles and one end of said toggle-levers being 50 operatively connected to said looper, and the other end of said levers being connected to a fixed support, a fixed support, a rotating part, means for rotating said part once to two rotations of the main shaft, and means for connecting said rotating part and said toggles, whereby said looper is reciprocated twice to one rotation of said rotating part; substantially as described.
- 55 9. In an overseaming-machine, the combination of the main shaft, a needle, means for operating the same, and complemental stitch-forming mechanism, comprising a spreader, means for operating said spreader, a looper, toggle-levers, one end of said toggle-levers being operatively connected to said looper, and the other end of said levers being connected to a fixed support, a fixed support, a rotating part, means for rotating said part once to two rotations of the main shaft, and means for connecting said rotating part and said toggles, whereby said looper is reciprocated twice to one rotation of said rotating part; substantially as described.
- 60 10. In an overseaming-machine, the combination of the main shaft, a needle, means for operating the same and complemental stitch-forming mechanism, comprising a looper, a rock-shaft on which said looper is supported, toggle-levers, one end of said toggle-lever being connected to said rock-shaft and the other end of said levers being connected to a fixed support, a fixed support, a rotating part, means for rotating said part once to two rotations of the main shaft, and means for connecting said rotating part and said toggles, whereby said looper is reciprocated twice to one rotation of said rotating part; substantially as described.
- 65 11. In an overseaming-machine, the combination of the main shaft, a needle, means for operating the same, and complemental stitch-forming mechanism, comprising a looper, toggle-levers, one end of said toggle-levers being operatively connected to said looper and the other end of said levers being connected to a fixed support, a fixed support, a rotating part, means for rotating said part once to two rotations of the main shaft, an eccentric carried by said rotating part, a bell-crank lever, a link connecting said eccentric and said bell-crank lever, a link connecting said bell-crank lever and said toggle-levers; substantially as described.
- 70 In testimony whereof I affix my signature in presence of two witnesses.
